United States Patent [19]

Weder et al.

US00D352918S

[11] Patent Number: Des. 352,918

[45] Date of Patent: ** Nov. 29, 1994

[54] FLOWER POT COVER

- [75] Inventors: Donald E. Weder; Joseph G. Straeter, both of Highland, Ill.
- [73] Assignee: Highland Supply Corporation, Highland, Ill.
- [**] Term: 14 Years
- [21] Appl. No.: 808,566
- [22] Filed: Dec. 16, 1991

Related U.S. Application Data

- [63] Continuation-in-part of Ser. No. 710,272, Jun. 4, 1991, which is a continuation-in-part of Ser. No. 617,454, Nov. 21, 1990, and a continuation-in-part of Ser. No. 411,249, Sep. 22, 1989, and a continuation-in-part of Ser. No. 411,247, Sep. 22, 1989, and a continuation-in-part of Ser. No. 411,245, Sep. 22, 1989.

[57] CLAIM

The ornamental design for a flower pot cover, as shown and described.

DESCRIPTION

FIG. 1 is a perspective view of a flower pot cover showing our new design;
FIG. 2 is a reduced side elevational view thereof;
FIG. 3 is a reduced top plan view thereof;
FIG. 4 is a reduced bottom plan view thereof;
FIG. 5 is a reduced side elevational view of the design of FIG. 1, the only difference being the angle of the skirt;
FIG. 6 is a reduced side elevational view of the design of FIG. 1, the only difference being the angle of the skirt;
FIG. 7 is a reduced side elevational of a second embodiment of the design of FIG. 1;
FIG. 8 is a reduced side elevational view of a third embodiment of the design of FIG. 1;
FIG. 9 is a reduced side elevational view of a fourth embodiment of the design of FIG. 1;
FIG. 10 is a reduced side elevational view of a fifth embodiment of the design of FIG. 1;
FIG. 11 is a perspective view of a sixth embodiment of the design of FIG. 1;
FIG. 12 is a reduced side elevational view thereof;
FIG. 13 is a reduced top plan view thereof;
FIG. 14 is a reduced bottom plan view thereof;
FIG. 15 is a reduced side elevational view of the design of FIG. 11, the only difference being the angle of the skirt;
FIG. 16 is a reduced side elevational view of the design of FIG. 11, the only difference being the angle of the skirt;
FIG. 17 is a reduced side elevational view of a seventh embodiment of the design of FIG. 1;
FIG. 18 is a reduced side elevational view of an eighth embodiment of the design of FIG. 1;
FIG. 19 is a reduced side elevational view of a ninth embodiment of the design of FIG. 1; and,
FIG. 20 is a reduced side elevational view of a tenth embodiment of the design of FIG. 1.

UNITED STATES PATENT AND TRADEMARK OFFICE
CERTIFICATE OF CORRECTION

PATENT NO. : Des. 352,918
DATED : November 29, 1994
INVENTOR(S) : Weder et al.

It is certified that error appears in the above-identified patent and that said Letters Patent is hereby corrected as shown below:

On the title page: Item [56]

under 'DESCRIPTION', line 12, after the word 'elevational', please insert --view--.

under 'DESCRIPTION', line 14, after the word 'FIG.', please delete "[", and insert --8--.

under 'OTHER PUBLICATIONS', line 1, please insert --Exhibit A. Curtis Wagner Co., Inc. Houston, TX, shows thick, stiff shiny red plastic pot cover with large scalloped border. (Photograph) Date Unknown.

under 'OTHER PUBLICATIONS', after the last paragraph, please insert the following new paragraph, --Exhibit O. SPEED COVER BROCHURE - THE SIMPLE SOLUTION..., © 1989.--
